ATTORNEY

UNITED STATES PATENT OFFICE.

CHARLES O. ROWLEY, OF TOLEDO, OHIO.

BURNER.

Application filed December 2, 1921. Serial No. 519,352.

To all whom it may concern:

Be it known that I, CHARLES O. ROWLEY, a citizen of the United States of America, residing at Toledo, Lucas County, Ohio, have invented new and useful Burners, of which the following is a specification.

This invention relates to burners for liquid fuel.

This invention has utility when incorporated in a gravity supply of oil for natural draft furnaces.

Referring to the drawings:

Fig. 1 is a section of a furnace showing an embodiment of the invention incorporated therewith;

Fig. 2 is a detail view with parts broken away, of the burner proper;

Fig. 3 is a plan view with parts broken away, showing the burner flue on the line 20 III—III, Fig. 2; and

Fig. 4 is a fragmentary side elevation showing supply line for fuel as entering burner proper.

A hot air furnace 1 is shown as provided with a combustion chamber 2 having fire door 3 as normal fuel supply therefor. Below this combustion chamber 2 is a grate 4 over ashpit 5 having ashpit door 6 in communication therewith.

A liquid fuel tank 7, say for a low grade fuel oil, is shown as having valve control outlet 8 past gravity strainer 9 to fuel supply line 10 extending through ashpit door 6 to the ashpit 5 below the grate 4. This fuel supply line 10 is shown as extending by way of guide tube 11 into central flue 12 of the burner. The position of this fuel supply line is adjusted as to the pipe 11 by set screws 13.

This central vertical flue 12 of the burner is shown as having a lower enlarged section 14 resting within flange 15 of base plate or pan 16 for the burner. In starting the burner the valve 8 is open and the supply of fuel is delivered into the flue 12 and such is ignited say by dropping a flame thereinto. At first this liquid burns in the bottom of the pan 16. Near the bottom of this pan 16 or within this portion 14 of the flue 12 there is inwardly extending flange 17 below air supply openings 18, 19. This flange 17

protects the fuel so that the air is directed thereover in burning the liquid fuel in starting the combustion. Thereafter the air supply is so directed in this fuel combustion 55 that there is eliminated or minimized the coking action.

As the burner warms up, the combustion, being incomplete in this lower region, is aided by further air supply through openings or ways 20 in the region 12 of the flue. As atmospheric conditions as well as fuel conditions vary, there is occasion frequently for adjusting this secondary air supply. To this end, surrounding this flue 12 adjacent 60 these annular series of openings 20, is a sleeve 21 having openings 22 therein which may be adjusted more or less into register with the openings 20, by shifting handle 23 extending through the ashpit door 6. Full 65 cutting off of the air supply of these openings 20 is not permitted because the opening 24 at the inlet pipe 11 is only elongated sufficiently to take air fully open and for incomplete shutting off of the opening of the 70 secondary air supply. Air is also supplied around the pipe 10 through the sleeve 11, and additionally keeps such supply of fuel from coking in the pipe 10. As the burner warms up there is a generous rolling out 75 of the flame and the valve 8 may be turned down to allow the dripping as a supply freely flowing for falling of the fuel supply into this flue 12. This generous rolling out of a white flame may be more or less 80 confined to the flue 12 by introducing back pressure, say by having legs 25 rise from this flue 12 to carry a hood or cap 26 having a skirt 27. As the burner warms up in 85 operation this flue 12 reaches incandescence 90 and there is accordingly a carburetor proper formed by this burner in its actual operation, the carburation stage occurring in the chamber, and in practice it has been found that such does 95 not choke or clog the supply line 10. In practice, this avoidance of coking in the supply line 10 is a situation not arising when delivery end 28 of this supply line 10 is deflected slightly downwardly so that there 100 is most free flow of the liquid supply as it enters the flue 12.

In this operation of the burner it is very desirable that all of the air be supplied to the flue 12 below the upper outlet portion 29 thereof. To this end there is disposed 5 upon the grate region 4 a baffle 30 coming up snugly about the flue 12 and completely closing ashpit 5 from the combustion chamber 2. This baffle 30 is a means insuring that all of the air supply for combustion is 10 to the flue below the flue discharge opening. Accordingly, with ample air supply through the ashpit door 6 there is all the air, both primary and secondary, supplied to this burner for the combustion in the combustion chamber 2.

In some instances in practice there may be advantage in supplying water as a steam with the burner, to thereby increase the efficiency of combustion. To this end water 20 supply valve 31 in water supply line 32 may be adjusted for just supplying a seeping or dripping of water to coil 33 about the enlargement 14 of the flue 12. This generates steam in this line 33 to be discharged by way 25 of duct 34 into the flue 14, 12.

In practice this burner is one which will operate quietly and handle low grade or cheap oil for effective complete combustion. This accordingly produces a clean fuel with 30 out smoke, and the roar even in normal operation say in a hot air heated house, is not such as to cause disturbance in the rooms above, as it is not really a roar but a sort of quiet hum. The flame is a voluminous rolling 35 out white flame with considerable heat value and in the burner combination as herein disclosed is one which can have the heat units thereof effectively used in this burner either for hot air, steam or other purposes, and so 40 disposed in installation as not to act deleteriously upon the furnace proper.

While the valve 8 may adjust the initial supply of fuel from the tank 7, it is advantageous to provide in the line 10 an additional control valve 35 which may be adjusted to regulate the flow for uniform delivery at an adjusted slow rate. This flow may be rendered more uniform by further providing in this line 10 between the valve 50 35 and the burner a T 36 with a riser 37 therefrom. This riser 37 is of sufficient height that there may not be overflow, while it further serves as an air intake for accelerating the flow of the fuel from the valve 35 55 into the burner.

What is claimed and it is desired to secure by Letters Patent is:

1. A burner comprising a gravity supply line, means for adjusting the flow of fuel 60 from said line, a combustion chamber having therein a pan and a flue upward from the pan, said line serving as means for conducting a fuel supply for freely flowing therefrom for falling into the flue toward 65 the pan centrally thereof, there being air

supply ways into the flue in annular series adjacent the pan and adjacent the fuel supply into and through the flue, said flue having an upper discharge opening, means for confining distribution of air supply to the flue 70 to below said discharge opening, and means for holding heat in the flue as a chamber to approximate incandescence.

2. In a furnace provided with a combustion chamber and an ashpit, a burner in 75 said pit, said burner comprising a gravity supply line, means for adjusting the flow of fuel from said line, a combustion chamber having therein a pan and a flue upward from the pan, for extending upward into the furnace combustion chamber, said line serving as means for conducting a fuel supply for freely flowing therefrom for falling into the flue 80 adjacent the pan and adjacent the fuel supply into and through the flue, said flue having an upper discharge opening, a baffle at the grate line of the air supply to the furnace combustion chamber to through the 85 flue opening, and means for holding heat in the combustion chamber entering portions of the flue for assisting combustion.

3. A burner comprising a gravity supply line, means for adjusting the flow of fuel from said line, a combustion chamber having therein a pan and a flue upward from the pan, said line serving as means for conducting a fuel supply for freely flowing therefrom for falling into the flue toward 90 the pan centrally thereof, there being air supply ways into the flue adjacent the pan and adjacent the fuel supply into and through the flue, said flue having an upper discharge opening, a skirted cap spaced 95 from the opening, and means for confining distribution of air supply to the flue to below 100 said discharge opening.

4. A burner comprising a gravity supply line, means for adjusting the flow of fuel 110 from said line, a combustion chamber having therein a pan and a flue upward from the pan, said line serving as means for conducting a fuel supply for freely flowing therefrom for falling into the flue toward 115 the pan centrally thereof, there being upper and lower air supply ways into the flue adjacent the pan and adjacent the fuel supply into and through the flue, means for adjusting the upper air supply ways, draft 120 retarding heat holding means for the upper portions of the flue, said flue having an upper discharge opening, and means for confining distribution of air supply to the flue to below said discharge opening.

5. A burner comprising a gravity supply line, means for adjusting the flow of fuel from said line, a combustion chamber having therein a pan and a flue upward from the pan, said line serving as means for con- 125

ducting a fuel supply for freely flowing therefrom for falling into the flue toward the pan centrally thereof, there being air supply ways into the flue adjacent the pan and adjacent the fuel supply into and through the flue, said flue having an upper discharge opening, means for confining dis-

tribution of air supply to the flue to below said discharge opening, and a steam coil heated by the flue for delivering steam into 10 said flue.

In witness whereof I affix my signature.

CHARLES O. ROWLEY.
